UNITED STATES PATENT OFFICE

HUBERT C. ROBINSON, OF DALLAS, TEXAS

OIL BURNER

Application filed March 10, 1930. Serial No. 434,637.

This invention relates to an oil burner characterized by certain improvements and refinements as contrasted with a similar oil burner shown in Patent 1,701,484, granted February 5, 1929.

In carrying the present invention into practice, I have evolved and produced a novel structural organization which is simplified and distinguishable in that it involves the utilization of a novel revision in structure, wherein the parts are especially shaped and mechanically co-related to better fulfill the requirements of a burner of this class.

It is my aim to generally improve upon the aforesaid patent, and similar patented and marketed burners by providing one which is susceptible of consuming low-grade fuel oils, and to accomplish this result through effective co-mingling and mixing of the oil vapors and air, whereby to develop a highly combustible fuel susceptible of producing an intensely hot and continuous flame.

The specific details and their relative arrangement and association will become apparent from the following description and drawings.

In the drawings:

Figure 1 is a top plan view of the principal parts of the burner as constructed in accordance with the present invention.

Figure 2 is a central vertical sectional view through the same with parts shown in elevation.

Figure 3 is a horizontal section on the plane of the line 3-3 of Figure 2.

Figure 4 is a similar sectional view on the line 4-4 of Figure 2.

Figure 5 is a view observing the discharge end of the cast body.

Figure 6 is a view of the opposite end of the body showing the uncovered ignition hole.

Figure 7 is an elevational view of the slide cover plate removed.

The entire assembly may well be seen in Figure 2. The casting 8 is in the nature of a hollow box-like body which is shaped to define an efficient mixing and combustion chamber. The top 9 is substantially flat. The rear end portion is rounded somewhat as in-

dicated at 10 in Figure 1 and the bottom is of curvate form as indicated at the point 11.

The end 12 is completely open and substantially rectangular in configuration. This is the flame discharge end. At the opposite end 10 is an ignition hole 13 and on the exterior is a U-shaped rigid guide 14 which is constructed to provide a keeper for holding the cover plate 15 in place. This cover plate is of the configuration shown in Figure 7 and includes a finger hook 16 to facilitate manipulation. Incidentally, I propose to insert a wad of cotton or the like therein and to ignite the cotton through this hole to start the burner into operation.

There is a hole 17 in the bottom of the body defining what may be designated as a secondary atmospheric air inlet, and arranged in alignment with this and projecting into the interior of the body is a hollow standard 18 having suitably shaped air intake slots 19. The top 20 of the standard is formed with a centralized socket which functions as a bearing for reception of the lower end portion 21 of a rotary fan shaft 22.

A bladed fan or mixing device 23 is mounted on this shaft just above the top of the standard and below the top 9 of the body so as to provide the desired clearance. This fan is located beneath a relatively large air intake hole formed in the top of the box and surrounded by an upstanding annulus or rim 24. A cup-like housing 25 is fitted telescopically over this annulus and provided with a multiplicity of air inlet openings 26.

The numeral 27 designates a cylindrical tubular nozzle which extends down through the housing and into the main inlet hole, the upper end of this nozzle having a lateral connection 28 in which the oil supply pipe 29 is connected. It will be observed that the fan shaft extends upwardly through the nozzle and is journaled in a bearing hole in the top of the nozzle as seen clearly in Figure 2. This provides the desired mounting for the ignition fan.

The gist of the invention, it will be seen, is in the novel assemblage of parts comprising the flat top, open-ended box defining a suitable mixing and combustion chamber, said

box having the primary air inlet opening in its top surrounded by the upstanding rim constituting the retaining means for the apertured cup-like housing. The housing constitutes a novel mounting and suspension means for the nozzle which depends into the main air inlet and terminates within the rim 24.

On large burners, the secondary air inlet 10 17 is located axially beneath the main air inlet and this is important as it affords additional supply of air. Then too, there is novelty in the utilization of the upstanding hollow conical standard which functions as 15 a primary bearing for the lower pointed end of the rotary fan shaft. This arrangement affords concentration of mechanism and systematizes the location of parts for facility in operation.

20. This being a natural draft burner, the primary air passes through the air inlet holes 26 in the housing 25 and then down through the main air inlet opening in the top of the box, causing the mixing and spraying fan to 25 revolve at relatively high rates of speed. The fuel line for the oil, indicated at 29, functions under the action of gravity and is controlled by a suitable regulating valve (not shown).

30. The lighting of the burner is simple and 95 expedient. I simply place a piece of waste or cotton into the box 8 through the ignition hole 13, at which time the plate 15 is open. A small amount of oil is allowed to drip 35 through the nozzle onto the waste, and to saturate it to a sufficient degree. I then light the saturated waste material, letting this burn for a second, at which time the door 15 is closed.

40. I then open the feed line valve slightly and allow a small portion of the oil to drip through the nozzle against the flaming waste, causing the desired vaporization of fuel. The oil vapors mix with the incoming air and 45 the natural suction developed therein produces the desired mixing and developing of highly combustible fuel.

This burner can be installed easily in any stove, furnace, stack, boiler or the like, and 50 used for heating or power, and it will save fifty per cent of fuel, it is believed.

It is thought that persons skilled in the art to which the invention relates will be able to obtain a clear understanding of the invention after considering the description in connection with the drawings. Therefore, a more lengthy description is regarded as unnecessary.

Minor changes in shape, size, and rearrangement of details coming within the field of invention claimed may be resorted to in actual practice if desired.

I claim:

60. In a burner of the class described, a hollow body having a main air inlet at its top 65

surrounded by an upstanding annular rim, said body being open at one end to provide a flame discharge, having an ignition hole at the opposite end and a closure therefor, the bottom of the body being formed with a secondary inlet and an upstanding hollow conical standard provided with air passages, the top of said standard being formed with a socket constituting a bearing, an apertured housing fitted telescopically over said rim, a nozzle fastened to said housing and depending down to the housing and into the air inlet, a fuel feed line connected with said nozzle, and a fan located in said body adjacent said air inlet and having a vertical shaft, the lower end of the shaft being journaled for rotation in the socket in said standard, the upper end portion of the shaft extending through the nozzle and being journaled for rotation in a bearing hole formed in the top of the nozzle.

In testimony whereof I affix my signature.

HUBERT C. ROBINSON.
